UNITED STATES PATENT OFFICE.

CARL HARRIS, OF LOWER LAKE, CALIFORNIA.

GATE.

No. 804,840.

Specification of Letters Patent.

Patented Nov. 21, 1905.

Application filed August 17, 1904. Serial No. 221,076.

To all whom it may concern:

Be it known that I, CARL HARRIS, a citizen of the United States, residing at Lower Lake, in the county of Lake and the State of California, have invented a new and useful Improvement in Gates, of which the following is a specification.

This invention relates to that class of gates known as "farm-gates" adapted to be opened from a vehicle. The object of the invention is to provide a gate of this class which can be readily opened and closed.

The invention consists, essentially, in a vertical and horizontally movable gate counterbalanced by suitable weights, whereby the use of hinges and fastening devices are avoided.

The invention also consists in the novel features of construction and combination of parts hereinafter described, particularly pointed out in the claims, and shown in the accompanying drawings, in which—

Figure 1 is a perspective view of the gate. Fig. 2 is a side elevation showing the gate partly opened, and Fig. 3 is a vertical section taken at right angles to Fig. 2.

In constructing the gate I employ parallel upright posts A, having preferably three pairs of these posts, two pairs being arranged opposite each other on the sides of the roadway and the third pair being arranged off the roadway and in alinement with the other pairs. The tops of the posts are connected by suitable timbers A' and A'', serving to firmly brace them. The two outer pairs of posts A carry also adjacent their upper ends transversely-arranged end boards A³, and a rod B has its ends carried by the end boards A³, the rod B passing between the posts A forming each pair and parallel to the brace-timbers A' and A'' in a slightly-lower plane. The center pair of posts A are shorter than the outer pairs and at their upper ends each carries a cross-head A⁴, from the ends of which extend uprights A⁵, upon which the timbers A' rest. A boxing or framework is thus formed, above which is arranged a transverse timber A⁶, from which depends a stop A⁷, through which the rod B passes, and the cross-piece A⁶ also carries a depending bracket, in which is swiveled a pulley C. Grooved rollers D travel on the rod B, which forms an elevated rail or track, and carry hangers, to the lower ends of which are connected a bar D'. At the ends of the bar D' are dependent pulleys D''. The gate E is a rectangular frame of any desired construction adapted to move between the posts of

each pair and to extend from one pair of posts to an adjacent pair. Pivoted at the center of the upper edge of the gate E is a lever F, the lower end of which is pivoted between the posts forming the center pair. Cables G are connected to the gate adjacent the upper corners of the gate, and each cable is passed over a pulley D² and supports counterbalancing-weights H.

Arranged at one side of the roadway and some distance from and substantially opposite the center of the frame formed by the posts A and timbers or beams A' is a post J, having the projecting arm J' extending over the roadway. This arm carries a pulley J². A cable K is connected at one end to upper frame of the gate E midway the ends of the gate and is passed over the pulleys C and J², the free end of the cable K hanging within easy reach of an occupant of a vehicle and carrying a weight or handle K' on said end.

The operation of the gate will be obvious. By drawing downward on the handle K' the gate will be lifted vertically between the posts of the central pair and will swing in the arc described by the lever F, the counterbalancing-weights H aiding in the vertical movement of the gate, and by reason of the weight of the moving mass and the momentum of the bar D' and pulleys D, which support the gate when lifted from the ground, the gate will be carried past the position where the lever F is in a vertical position and will swing into position between the center pair of posts and the posts A set off from the roadway, leaving the latter clear. The gate can be brought back to its original position in the same manner, and it will be obvious that to open or close the gate from each side it is only necessary to duplicate the post J and connecting parts. As no hinges are employed there is no tendency for the gate to sag, and no fastening device is needed. By using the weights H but a slight pull is required on the handle K' to move the gate into the desired position.

Having thus fully described my invention, what I claim as new, and desire to secure by Letters Patent, is—

1. The combination with posts, a track supported by the posts, a vertically and horizontally movable gate between the posts and below the track, a lever pivoted adjacent the gate at one end and to the gate at the opposite end, rollers on the track, pulleys suspended therefrom, cables attached at one end

to the gate and running over the pulleys, respectively, weights attached to the free ends of the cables, and means for moving the gate in the arc described by the lever.

5 2. A gate of the kind described comprising posts, a rod carried horizontally by the posts, grooved rollers adapted to travel on the rod, a bar connecting the rollers, pulleys carried by the bar, a gate-frame, cables connected to 10 upper corners of the gate-frame and passing

over the pulleys carried by the bar, weights on the free ends of the cables, pulleys carried by the posts, and a cable connected to the gate midway the ends of the gate and passing over the last-mentioned pulleys.

CARL HARRIS.
